UNITED STATES PATENT OFFICE.

SAMUEL HOAR, OF VIRGINIA, MINNESOTA.

MECHANICAL SHOVEL.

1,322,570.

Specification of Letters Patent. Patented Nov. 25, 1919.

Application filed January 14, 1919. Serial No. 271,056.

To all whom it may concern:

Be it known that I, SAMUEL HOAR, a citizen of the United States, residing at Virginia, in the county of St. Louis and 5 State of Minnesota, have invented certain new and useful Improvements in Mechanical Shovels, of which the following is a specification, reference being had therein to the accompanying drawing.

10 This invention relates to mechanical shovels and the embodiment here illustrated and described is especially designed for tunneling purposes where room for operating the device may be considerably restricted such as experienced in coal, iron or 15 other mines and for which purpose my present invention includes a convertible combination of shoveling means.

It is evident that this or a slightly modified form may be used with equally good results where open shoveling is required and such machines employed.

The principal object of the invention is to provide a more practical mechanical 25 shovel than heretofore known and one requiring as little space as possible in which to operate.

Another object is to provide convenient 30 convertible means in the event of exceptional conditions arising preventing the turning around of the shovel while working and whereby material being shoveled may be passed directly over the machine longitudinally thereof.

35 Still other objects and advantages of the novel combination of parts will appear in the further description of the invention.

In the accompanying drawings forming 40 part of this application and in which like reference characters represent like parts:—

Figure 1 is a side elevation of one embodiment of my invention.

Fig. 2 is a front elevation of Fig. 1 except that a modified form of shovel and 45 mounting therefor is illustrated.

Fig. 3 is a side elevation partly in section of Fig. 2,

Fig. 4 is a top plan view of Fig. 2, and

Fig. 5 is a transverse sectional view on the 50 line 5—5 Fig. 1.

1 represents a tram car mounted upon four wheels 2—2 and 3—3, the latter or rear wheels being considerably larger in

diameter than the former for the purpose of producing a forward downward inclination to the body of the car, the particular object of which will appear later.

55 A turntable having co-operative interlocking parts 4 and 5 is mounted upon the car body and supports the adjustable superstructure indicated at 6, the floor of which is completely covered over with a suitable deck 7.

60 The superstructure 6 may be of any desired form of fabrication to provide the necessary strong support for the operating parts of the machine.

65 I have shown the upright ends of the superstructure as being composed of angle bars 8—8 at the rear end and 9—9 at the forward end, each pair being tied together and strengthened by suitable end plates, 10 at the rear and 11 at the front end.

70 Upon the upper extremities of these angle bars is supported the shovel carriage track.

75 In the structure shown in Fig. 1, each rail of this track comprises an upright web 12 which is firmly attached to the upper ends of the angles 8 and 9 and forms the inner wall of the rail. Longitudinally of 80 the outer lower edge of the web 12 is securely riveted the angle bar 13 which forms the rail proper and upon which the wheels of the reciprocable shovel carriage rest. To the upper outer edge of the web is 85 fastened a bar 14 similar to the bar 13 except that it is square in cross section, and which acts as a guide to the wheels of the shovel carriage to prevent them being raised from the bar 13 and becoming dislodged, the construction of the two rails being identical.

90 The spacing of the rails apart is approximately one half the width of the superstructure upon which they are mounted, this being found to result in a well balanced and proportioned machine for the purpose intended.

95 The front supporting bars 9 are considerably shorter than the rear bars 8 for the purpose of producing an inclination toward the forward end of the track, such inclination being downward.

100 15 represents the shovel carriage which has a forwardly extending upper portion 105 16 upon which is pivotally mounted the

shovel or dipper arm 18 having supports 17 attached thereto and mounted upon the transverse shaft 33 on the carriage.

The carriage may be of any desired construction, but is here shown as composed of angle bars for the side frames and decked over with a suitable plate 19 reinforced with angles 20 and 21. The wheels 22 of the carriage, and of which there are two on each side thereof, operate intermediate of the bars 13 and 14 while the wheels 23 of which there is but one upon each side of the carriage are outside of the side frame of the carriage and only support the latter as auxiliary wheels. When the shovel is fully advanced the wheels 23 may project beyond the forward end of the rails.

The dipper arm or stick, as it is frequently called, is composed of two suitably shaped channel bars attached at one end to either side of the dipper 24 and at their opposite ends 25, are drawn toward each other and have fixed therebetween, by suitable bolts 26, the extension 27. To the free end of this extension is attached the operating line 28 leading over the sheave 29 on the shaft 30 from the winding drum 31, which latter is operated in any desired manner by a suitable motor 32. In this instance, the motor illustrated is a Dake steam or compressed air motor.

A single line only is required for operating the dipper as the material engaging end is at all times heavier than the handle end and will naturally go to its work by gravity.

A second Dake motor is installed within the machine and operates, by means of a suitable worm drive indicated at 35, the winding drum 36. Upon this drum is mounted the carriage operating cable 37, one end of which passes about the sheave 38 on the shaft 30 and thence to the under side of the deck plate 19 of the dipper carriage where it is secured in any desired manner. The opposite end of the cable 37 passes over the sheave 39 mounted on the shaft 40 at the opposite end of the machine to that in which the shaft 30 is carried, and thence to the under side of the deck 19 of the shovel carriage. By this means the carriage is reciprocated longitudinally its track at the will of the operator who has control of the engine 34, it being well known that these engines, as well as many other makes, are readily reversible by the manipulation of a single lever control.

I have found by experience that a worm driven winding drum of this character is exceptionally efficient in combination with a shovel supporting carriage mounted upon an inclined track directly thereabove.

It will be readily understood that a carriage thus mounted will constantly seek the lower end of the track and the use of the

worm drive avoids the necessity of constant attention by the operator in preventing movement of the carriage by gravity. The movement of the carriage is also absolutely positive with such driving mechanism. 70

A third Dake engine or motor 41 is mounted on the machine, is connected to and operates the vertical shaft 42 carrying a spur gear 43 at its lower end which meshes with the ring gear 44 fixed to the tram car 1 and by which the rotation of the superstructure of the device is accomplished.

In some instances it is found necessary to make the superstructure of the machine as low as possible to provide sufficient head 80 room for operating the shovel and this at times, results in interference with loading the higher types of tram cars when the shovel is swung around for such purpose, its elevation being limited to a position in 85 which the shovel and handle are substantially parallel with the tram track.

At such times, is when the combination of the inclined carriage track on the rotatable superstructure and inclined tram car afford 90 the necessary means for elevating the loaded shovel sufficiently for practical purposes when turned about over the high tram car, as the shovel will thus be automatically elevated. 95

Another advantageous feature of this combination, and one experienced in both forms of shovel mountings here illustrated, is that the angle of the ground engaging lip of the shovel becomes exceptionally well 100 adapted to digging somewhat below the level of the track bed, which results in great convenience and efficiency.

In the modified form of carriage mounting and shovel as illustrated in Figs. 2, 3 105 and 4, the tram car, superstructure, arrangement of motors and operating parts are identical to those shown in Fig. 1 and above described, the latter being that form of machine better adapted for common use. But 110 the modified form of shovel and mounting is provided for special tunnel work, and form an auxiliary part of the general purpose machine.

In this form, the shovel carriage track is 115 of the same general form of fabrication as that shown in Figs. 1 and 5 except that the wheel engaging portions are facing inwardly toward each other instead of outwardly, that is to say, the wheel guiding 120 bars 45 and 46 are on the inside of the webs 47 and the entire shovel carriage operates intermediate of the webs of the track. The traction wheels of the carriage are illustrated at 49 and 50.

The track in this instance is formed with a hump 51 therein instead of being a continuous incline as in the formerly described machine, the rear wheel portion thereof being approximately the length of the wheel 130

base of the carriage, but practically the same degree of inclination as the forward portion.

By this construction of track, the carriage, when drawn rearwardly, will assume the position shown in dotted lines Fig. 3 with the forward end tilted up considerably higher than the opposite end and this occurs just at the time of termination of the rearward travel of the carriage and when the load of the shovel is to be discharged. The shovel and handle are made the same width and approximate depth throughout, thus combining to form a chute through which the material is discharged in the accompanying cars to be loaded at the rear of the machine. The discharge of the shovel occurs when the carriage is brought to a sudden termination of its rearward stroke and the free end of the handle extends over the car being loaded.

The shovel is pivotally mounted on the transverse shaft 52 suitably journaled in the forward end of the carriage and has rigidly fixed thereto the arms 53 53 which form the support therefor.

The forward or material engaging end 54 of the shovel is of the same general form as that shown in Fig. 1 and may or may not be provided with an operative closure as shown in Fig. 1 and common to such shovels. The opposite end of the chute-like shovel handle is open at all times and the operating rope is attached and controlled identically with that illustrated in Fig. 1. The carriage control is also identical to that previously described except that the end of the line attached to the rear end of the carriage passes over a suitably installed guiding roller illustrated at 58.

From the above it is apparent that the changing from one machine to the other necessitates only the adjustment of the cable connections and the attachment of the carriage track to the upper ends of the angle bars 8-8 and 9-9.

In Fig. 2 is illustrated a suitable seat 55 resting upon a laterally projecting narrow platform 56, for the convenience of the operator. In front of this seat are mounted in any desired manner the three levers 57 by which the motors are controlled.

Having thus described my invention,

what I claim as new and desire to secure by Letters Patent, is:—

55

1. In a mechanical shovel, the combination with a tram car mounted upon wheels greater in diameter in the rear thereof than in the front and having a turn table thereupon, of a rotatable superstructure supported upon the car, an inclined track carried by the superstructure and extending from one end thereof to the other and a shovel reciprocably carried on the track.

60

2. In a mechanical shovel, the combination with a normally inclined tram car of the character described, of a rotatable superstructure upon the car having a track of greater inclination than that of the car body thereupon and extending from one end thereof to the other and a shovel reciprocally carried upon the inclined track.

65

3. The combination with a tram car having a rotatable superstructure thereupon and an inclined track in the upper portion of the superstructure extending from one end thereof to the other, of a carriage reciprocably mounted upon the track, a transverse shaft in the forward end of the carriage, a shovel support extending radially from the shaft, a shovel fixed to the support and spaced from the carriage, means for pivotally operating the shovel and means for reciprocating the carriage.

70

4. In a mechanical shovel, the combination with a tram car having a superstructure thereupon, of a superimposed humped track in the upper portion of the superstructure and extending from one end thereof to the other, a carriage reciprocably mounted within the track, a combination chute handled shovel pivotally and co-operatively carried by the carriage, means for pivotally operating the shovel and means for reciprocally operating the carriage whereby the contents of the shovel may be discharged over the superstructure and at the opposite end thereof to that at which it was shoveled.

75

40

5. In a mechanical shovel, the combination with a tram car having a superstructure thereupon, of a superimposed humped track in the upper portion of the superstructure and extending from one end thereof to the other, a carriage reciprocably mounted within the track, a combination chute handled shovel pivotally and co-operatively carried by the carriage, means for pivotally operating the shovel and means for reciprocally operating the carriage whereby the contents of the shovel may be discharged over the superstructure and at the opposite end thereof to that at which it was shoveled.

80

45

6. In a mechanical shovel, the combination with a tram car having a superstructure thereupon, of a superimposed humped track in the upper portion of the superstructure and extending from one end thereof to the other, a carriage reciprocably mounted within the track, a combination chute handled shovel pivotally and co-operatively carried by the carriage, means for pivotally operating the shovel and means for reciprocally operating the carriage whereby the contents of the shovel may be discharged over the superstructure and at the opposite end thereof to that at which it was shoveled.

85

70

7. In testimony whereof I hereunto affix my signature in the presence of two witnesses.
